CARTON MAKING MACHINE

Claude M. Stitt, Antioch, Calif., assignor to Fibre-board Products Inc., San Francisco, Calif., a corporation of Delaware

Application December 23, 1936, Serial No. 117,279

20 Claims.

(Cl. 93—49)

My invention relates to a machine for making cartons having depending legs; and the broad object of the invention is to provide mechanism for folding portions of the carton blank to form the legs.

Another object of my invention is to provide a machine operating in conjunction with a reciprocating head for forming the carton, and adapted to form collapsed legs by tucking inwardly portions of the blank prior to the formation of the carton by the head.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

20 Referring to the drawings:

Figure 1 is a side elevational view of a carton making machine embodying the improvements of my invention; and

Figure 2 is a plan view of the carton blank operated on by my machine.

Figure 3 is a plan view of the machine; and

Figure 4 is a perspective view of the carton formed by my machine from the blank shown in Figure 2.

30 Figure 5 is an end elevational view of the machine, looking in the direction of arrow 5 in Figure 1.

Figure 6 is a transverse vertical sectional view showing the leg forming mechanism, taken in a plane indicated by the line 6—6 of Figure 1.

Figure 7 is a longitudinal vertical sectional view of the leg forming mechanism, taken in a plane indicated by the line 7—7 of Figure 6.

40 Figures 8 to 13 are diagrammatic views illustrating the operation of the leg forming mechanism.

In terms of broad inclusion, my machine for making a carton having depending legs comprises means for tucking inwardly portions of a 45 carton making blank to form a leg. Means are preferably provided for applying adhesive to the tucked-in portions, and means are also preferably provided for applying pressure to the tucked-in parts to cement the leg forming portions together. A reciprocating head is preferably arranged for operation in time with the leg forming mechanism for folding up the walls of the carton, and means are provided for delivering the partially folded blank from the leg forming 50 mechanism to the head. A gluing mechanism is

also arranged to apply adhesive for cementing the walls together when they are folded up.

In greater detail, the machine embodying my invention is designed to fold a carton forming blank 2, such as shown in Figure 2, having longitudinal score lines 3 adapted to be folded to form legs 4 depending from the side walls 6 of the carton, as shown in Figure 4. The carton also has end walls 7 folded up from transverse score lines 8 and fastened to side wall tabs 9, 10 and has a cover 11 provided with a tuck 12. Diagonal crease lines 13 in the front side and end walls permit collapsing the set-up carton. This general type of carton is described in detail in the patent to Brown and Ford, No. 1,876,200, 15 issued September 6, 1932.

My machine is principally for the purpose of folding the legs 4 of the carton, and is shown as an attachment for a machine 14 (see Figures 1 and 5) having a reciprocating head 16 adapted 20 to engage the bottom forming portion of the blank and fold up the side and end walls 6 and 7. This latter machine is commonly known in the art as the "Brightwood" machine. The bed frame 17 of my machine lies in the same plane as the bed of the associated machine 14, and is supported by suitable legs 18.

As shown in Figures 1 and 3, the blanks to be folded are fed into the machine endwise so that the longitudinal lines 3 are parallel with the longitudinal axis of the machine. The blanks are fed from a chute 19 having a vertically adjustable front plate 21 under which the blanks are allowed to pass out one at a time. A movable block 22 at the rear of the chute operates to push 30 the lowermost blank out of the chute and into feed rolls 23. The reciprocating block 22 is operated by suitable mechanism from a drive sprocket 24, and a suitable clutch is preferably provided 35 in the mechanism and operated by a lever 26 40 for starting and stopping the block.

From rolls 23 the blank is fed into a gluing unit 26 having a pair of glue wheels 27 against which the blank is pressed by supporting rollers 28. These wheels are arranged to apply strips of 45 glue alongside the outer longitudinal lines 3 for purposes of securing together portions of the blank which are later folded into legs. The gluing unit and feeding mechanism are both driven from a sprocket 29 on shaft 31 by a chain 32 50 passing over sprockets 24 and 25 of the feed mechanism and a sprocket 33 on the supporting roller shaft of the gluing unit. An idler sprocket 34 is also provided for guiding the chain.

From the gluing unit the blank passes between 55

another pair of feed rolls 36 which deliver the blank into the leg forming mechanism. The latter, as best seen in Figure 7, comprises an upper head 37 supported on rods 38 slidably mounted in the frame of the machine and pressed downwardly by springs 39; downward movement of the head being limited by cap nuts 41 on the upper ends of the rods. The blank is pressed against this head and held in folding position by a plate 42 mounted on depending rods 43 also slidable in the frame of the machine and normally held in down position by springs 44. Plate 42 and the overlying head 37 are separated when a blank is being fed into the folding mechanism by rolls 36, and both the plate and head are elongated in shape to engage only the bottom forming portions of the carton blank between the crease lines 3 when the plate and head come together to clamp the blank.

20 The holding plate 42 is moved up by a cam 46 on shaft 47 journaled in the lower portions of the frame. Motion is transmitted from the cam by a lever 48 (see Figure 6) pivoted on the frame and carrying a follower roller 49 riding on the cam. An upwardly extending arm 51 is arranged with its lower end pivoted to the lever 48 and its upper end pivoted to a cross member 52 connected to and extending between the rods 43. By this arrangement the blank holding plate 42 is moved up and down when the shaft 47 rotates. Figures 8 to 13 show the motion of plate 42. The first action is to close the space between the plate and head 37 and press the blank up against the head. Continued upward movement of the plate 35 also moves the head upwardly against its spring pressure until the upper limit of movement is reached. In other words, the action of the parts is twofold; first, to hold the blank, and second, to give the blank thus held an upward movement.

40 Prior to the clamping of the blank between the plate and head, suitable fingers 56 operate to engage the ends of the blank at opposite sides of the plate to accurately position the blank so that the inside score lines 3 lie along the side edges of plate 42. As shown in Figure 6, the fingers 56 are slidably pivoted on fixed pins 57 working in slots 58 in the intermediate portions of the fingers. The lower ends of the fingers are pinned together to a lever 59 on a cross shaft 61. By this arrangement the fingers are given a simultaneous upward and closing motion to engage the end tabs 7 of the blank and center the blank on the plate 42.

45 Fingers 56 are normally held down and open by a spring 62 (see Figure 7) encircling shaft 61 and secured at one end to the frame and at the other end to a collar 63 on the shaft. The fingers are operated by another lever 64 on shaft 61 and carrying a pin 66 lying in the forked end of a rod 67 pivoted at its lower end to an arm 68 having a follower roller 69 riding on a cam 71 fixed on shaft 47.

50 After the blank is positioned and clamped between plate 42 and head 37, suitable fingers 72 come into operation to tuck inwardly the portions of the blank between the longitudinal crease lines 3 to form the carton legs 4. As best shown in Figures 8 to 10, fingers 72 are positioned alongside the lower edges of head 37 so that the fingers press down the blank to start the tuck folding operation by reason of the upward movement of the blank. Subsequently fingers 72 move inwardly to tuck the blank under the edges of plate 42.

55 75 This latter movement of the tucking fingers is

effectuated by rotating shafts 73 on which the fingers are mounted. Both shafts carry segment gears 74, one of which is shown in Figure 7, meshed with worms 76 on a cross shaft 77 (see Figure 3). The latter shaft is in turn rotated by a rack 78 mounted on rod 79 pivoted to crank 81 on shaft 82. A lever 83, also on shaft 82, is actuated by a rod 84 having a forked end guided on shaft 31 and carrying a follower roller 86 riding in a cam 87 fixed on shaft 31. The cam imparts a reciprocating motion to rack 78, which in turn gives a swinging in and out motion to tucking fingers 72.

After the tuck is formed, means are provided for pressing the tucked in portions of the blank against plate 42 to glue the leg portions together. This is accomplished by moving pressure elements 88 up against the tucked in portions. Elements 88 are carried by a cross beam 89 slidably mounted on a pair of vertical rods 91 fixed in the frame of the machine; the beam being pressed upwardly by springs 92 encircling the rods. See Figure 6. Up and down motion is imparted to beam 89 by a pair of connecting rods 93 pivoted between the beam and cranks 94 journaled in the frame. The 25 crank shafts each have a gear 96 meshed with racks 97 carried by a plate 98 slidable vertically in guideways 99 on the frame of the machine. As best shown in Figure 7, plate 98 is provided with a follower roller 101 riding in a cam 102 on shaft 47.

As the racks 97 are reciprocated vertically by the cam, the crank shaft gears 96 are given a turning motion back and forth through a pre-determined arc, and the beam 89 is reciprocated vertically. This motion of the beam is such that in its upper limit of travel the elements apply pressure to the tucked in portions of the blank, as shown in Figures 11 and 12.

At the time when the tucking fingers 72 are 40 moving inwardly, means are provided for holding down the edges of the blank, and means are also provided for moving this edge holding means inwardly in time with the tucking finger movement. For this purpose a pair of plates 103 are slidably 45 mounted on beam 89 with suitable flanges 104 extending downwardly to guide the plates. Each flange is cut with teeth to provide racks 106 meshed with segment gears 107 on the pivot shafts 108 of connecting rods 93, so that when 50 beam 89 moves upwardly the plates 103 are simultaneously moved inwardly.

The edges of the blank are held down against plates 103 by suitable pivoted fingers 109 normally pressed upwardly and inwardly by springs 55 111. Fingers 109 are moved down against the blank by cams 112 mounted on another set of shafts 113. These shafts carry segment gears 114, one of which is shown in Figure 7, meshed with worms 116 on a cross shaft 117. See Figure 60 3. The latter shaft is rotated by a rack 118 carried by a rod 119 pivoted to a crank 121. The latter is actuated by a rod and cam, similar to rod 84 and cam 87. Motion of hold down fingers 109 is such that the fingers clamp down when 65 plates 103 are out, and then move inwardly with the plates when the tucking fingers 72 move inwardly. This following in of the edge holding means keeps the edges of the blank properly held, but at the same time allows the tucks to 70 be formed without stressing the blank material.

After the legs have been formed, and head 37 and plate 42 have been separated by downward movement of beam 89 to free the blank, the latter is pulled from the plate by a set of feed 75

rolls 122. See Figure 7. The first pair of these rolls are in position to engage the leading end of the blank whenever one is in the folding mechanism; but these rolls are normally inactive because they are held separated by links 123. When the folding is finished however, the links 123 pull down the upper roll to feed the blank forward. The action of the separable rolls is controlled by a lever 124 connected to link 123 and moved by a rod 126 (Figures 1 and 5) pivoted to an arm of a bell crank 127. The other arm of the crank carries a follower roller 128 riding on a cam 129 on shaft 47.

Feed rolls 122 deliver the partially folded blank onto a conveyor chain 130 (Figures 1 and 3) running transversely across the end of the machine. This conveyor then delivers the blank to the feed rolls 131 (Figure 5) of the "Brightwood" machine, which feed the blank to the plunger 16, at which point the side walls of the blank are folded up to complete the carton. While the blank is traveling along on the conveyor it passes through a second gluing unit 135 having a gluing roller 132 and a supporting roller 133. This gluing unit applies adhesive to the end tabs 7 of the blank for uniting these end walls to the side wall tabs 9 when the walls are folded up by the plunger 16.

Another feature of the machine, shown in Figure 5, is the provision of a second chute 134 for holding blanks to be folded into cartons similar to that shown in Figure 4, but without the legs. In this case, the leg folding mechanism is unnecessary, and the blanks are fed by a pusher block 136 and feed rolls 137 directly onto the conveyor chains 130; a widened plate 138 being arranged alongside the conveyor to guide the blanks.

My machine is designed to be driven from the shaft 139 of the "Brightwood" machine. A shaft 141 is journaled on the side of my machine, and is connected by a drive chain 142 for continuous rotation with the shaft 139. A chain 143 from the shaft 141 drives the conveyor chains 130, so that the latter are running whenever the "Brightwood" machine is operating. Gluing unit 135 is also driven at the same time by suitable connection with the chain drive 143. The main shaft 47 of my machine is driven by a chain 144 running on a sprocket 146 freely journaled on shaft 139, and also passing around a sprocket 147 on shaft 47. The drive is then continued from shaft 47 to shaft 31 by a gear and worm unit 148. Chain 144 also passes over a sprocket 149 on shaft 151, from which the various feed rolls 36 and 122 are driven. A belt drive 152 connects shaft 151 to shaft 153, and the latter in turn is geared to the feed roll shafts 154 by suitable gears 156. See Figure 6 wherein the feed roll shafts are shown together with the spring pressed mountings 157 for the upper roll shafts.

In order to put the leg folding mechanism in operation, means are provided for clutching the freely journaled sprocket 146 to shaft 139. For this purpose, and referring particularly to Figure 3, a clutch element 158 is slidably mounted for rotation on shaft 139 and is movable into engagement with sprocket 146 by a shift lever 159 on slide rod 161 having a handle 162 adjacent one side of the machine.

When it is desired to use the chute 134, for folding cartons without legs, the leg folding mechanism is disconnected by disengaging clutch element 158. Means are provided for then hooking up the feed mechanism for chute 134. This is accomplished by a clutch element 163 freely journaled on shaft 141 and engageable with the hub

of sprocket 165 on which the chain 142 runs. Element 163 also carries a sprocket 164 for driving a chain 166 which runs over sprocket 167 of the feed mechanism and also sprocket 168 of the feed rolls 131. Clutch element 163 is operated by a shift lever 169 also mounted on slide rod 161, so that an operator may optionally engage the clutch elements 158 and 163 by manipulation of handle 162. Figure 3 shows clutch 158 engaged and clutch 163 disengaged, meaning that the leg folding mechanism is in operation and the feed from chute 134 is inactive. Chute 134 and gluing unit 135 are omitted in both Figures 1 and 3 to simplify these views.

In the operation of my machine, for folding cartons having depending legs, the blanks 2 are fed forwardly one at a time from the chute 19 to gluing unit 26. As the blanks pass through this unit two strips of glue are applied alongside the outer longitudinal score lines 3. From the gluing unit a blank is fed into the leg folding mechanism by principal holding means comprising head 37 and pressure plate 42. As illustrated in Figures 8 to 13, an incoming blank is accurately positioned between the plate 42 and head 37 by positioning fingers 56. At the same time plate 42 moves up to clamp the blank in the folding position. Further upward movement of plate 42 then elevates the blank against fingers 72 and starts folding the blank about the edges of the plate.

Simultaneously the blank supporting plates 103 move up to clamp the edges of the blank against fingers 109. Fingers 72 then swing inwardly to complete the tucking operation, and at the same time plates 103 and gripping fingers 109 move inwardly to allow for the material being taken in by the tucks. Tucking fingers 72 then swing back, and the beam which supports plates 103 continues to rise until elements 88 press up against the tucked-in portions of the blank. The beam then lowers to depress elements 88 and plates 103, thus freeing the edge portions of the blank. Simultaneously plate 42 starts down and continues down to a point below the lower limit of travel of head 37, thus separating the head and plate to release the blank.

As soon as the blank is released the normally separated feed rolls 122 come together to start feeding the partially folded blank out of the leg folding mechanism. This feeding of the blank between rollers and otherwise treating the blank as a sheet is possible because the folded legs at this time are collapsed and lie substantially in the plane of the blank. Pressure of rolls 122 also helps to press the tucked-in portions against the body of the blank and gives time for the glue to partially set.

From rolls 122 the blank is discharged on conveyor chains 130 by which it is fed in a direction at right angles to its former path. As the blank passes through gluing unit 135 it receives spots of glue on the end wall tabs 7 and then passes into the "Brightwood" machine. Feed rollers 131 pass the blank to its folding position under the plunger 16 which then descends to fold up the walls of the blank and press the tabs 9 against the glue on the end walls. As the side walls 6 are folded up the legs 4 automatically fold down by reason of the fact that they form a continuation of the side walls.

If it is desired to fold blanks into cartons without legs, the drive to the leg folding mechanism is disconnected and blanks are fed from chute 134. These blanks are discharged on conveyor

chains 130 and are fed directly through gluing unit 135 and into the "Brightwood" machine.

I claim:

1. A machine for making a carton having depending legs from a blank, comprising means 5 engaging intermediate portions of the blank for holding the blank in a folding position, means for tucking inwardly portions of the blank to form a leg and means for holding the edge portions of the blank during the tucking operation.
  - 10 2. A machine for making a carton having depending legs from a blank, comprising means for holding the blank in a folding position, means for tucking inwardly portions of the blank to form a leg, and means separate from said tucking 15 means for applying pressure to the tucked in portions.
  - 20 3. A machine for making a carton having depending legs from a blank, comprising means for feeding the blank to a folding position, positioning fingers engaging the edges of the blank for accurately positioning the blank in said position, means for holding the positioned blank, and means for tucking inwardly portions of the blank to form a leg.
  - 25 4. A machine for making a carton having depending legs from a blank, comprising a finger for tucking inwardly portions of the blank to form a leg, means for moving the blank relative to the finger to start the tucking operation, means for moving the finger to complete the tucking operation, means for withdrawing the finger, and means for applying pressure to the tucked in portions.
  - 30 5. A machine for making a carton having depending legs from a blank, comprising a head against which the blank may be pressed to hold it in folding position, a plate for pressing the blank against the head, and means for tucking inwardly over the rim of the plate portions of the blank to form a leg.
  - 35 6. A machine for making a carton having depending legs from a blank, comprising a head against which the blank may be pressed to hold it in folding position, a plate for pressing the blank against the head, means for tucking inwardly over the rim of the plate portions of the blank to form a leg, and means for pressing the tucked in portions against the plate.
  - 40 7. A machine for making a carton having depending legs from a blank, comprising a head against which the blank may be pressed to hold it in folding position, a plate for pressing the blank against the head, a finger for tucking inwardly over the rim of the plate portions of the blank to form a leg, means for moving the plate, head and interposed blank relative to the finger to start the tucking operation, and means for moving the finger to complete the tucking operation.
  - 45 8. A machine for making a carton having depending legs from a blank, comprising a head against which the blank may be pressed to hold it in folding position, a plate for pressing the blank against the head, a finger for tucking inwardly over the rim of the plate portions of the blank to form a leg, means for moving the plate, head and interposed blank relative to the finger to start the tucking operation, means for moving the finger to complete the tucking operation, means for pressing the tucked in portion against the plate, and means for separating the plate and head to free the folded blank.
  - 50 9. A machine for making a carton having depending legs from a blank, comprising a spring 75
- pressed head against which the blank may be pressed to hold it in folding position, a plate for pressing the blank against the head, a finger for tucking inwardly over the rim of the plate portions of the blank to form a leg, means for moving the plate upwardly against the spring pressure on the head to move the plate, head and interposed blank relative to the finger to start the tucking operation, and means for moving the finger to complete the tucking operation.
- 10 10. A machine for making a carton having depending legs from a blank, comprising a spring pressed head having a lower position of rest and against which the blank may be pressed to hold it in folding position, a plate for pressing the blank against the head, a finger for tucking inwardly over the rim of the plate portions of the blank to form a leg, means for moving the plate upwardly against the spring pressure on the head to move the plate, head and interposed blank relative to the finger to start the tucking operation, means for moving the finger to complete the tucking operation, and means for lowering the plate below the rest position of the head to free the folded blank.
- 15 11. A machine for making a carton having depending legs from a blank, comprising means engaging intermediate portions of the blank to hold it in folding position with the edges of the blank extending outwardly beyond the holding means, means engaging said outwardly extending edge portions of the blank for holding the latter, and means for tucking inwardly portions of the blank between said means to form a leg.
- 20 12. A machine for making a carton having depending legs from a blank, comprising means engaging intermediate portions of the blank to hold it in folding position, means engaging edge portions of the blank for holding the latter, means for tucking inwardly portions of the blank to form a leg, and means for moving the edge holding means inwardly during the operation of said tucking means.
- 25 13. A machine for making a carton having depending legs from a blank, comprising a head against which the blank may be pressed to hold it in folding position, a plate for pressing the blank against the head, a finger for tucking inwardly over the rim of the plate portions of the blank to form a leg, means for moving the plate, head and interposed blank relative to the finger to start the tucking operation, means for moving the finger to complete the tucking operation, means for holding the edge portions of the blank, and means for moving the edge holding means inwardly in time with the movement of said tucking finger.
- 30 14. A machine for making a carton having depending legs from a blank, comprising a head against which the blank may be pressed to hold it in folding position, a plate for pressing the blank against the head, a finger for tucking inwardly over the rim of the plate portions of the blank to form a leg, means for moving the plate, head and interposed blank relative to the finger to start the tucking operation, means for moving the finger to complete the tucking operation, a movable element for pressing the tucked-in portions against the plate, means movable with said element for holding the edge portions of the blank, and means for moving the edge holding means inwardly in time with the movement of said tucking finger.
- 35 15. In a machine for making a carton having

depending legs from a blank, the combination with means for folding the blank to form the carton, of means for tucking inwardly portions of the blank to form a leg, and means for feeding the blank from the last mentioned means to said carton forming means.

16. In a machine for making a carton having depending legs from a blank, the combination with a reciprocating head for folding the blank to form the carton, of means for tucking inwardly portions of the blank to form a leg, and means for feeding the blank from the last mentioned means to said head.

17. In a machine for making a carton having depending legs from a blank, the combination with means for folding the blank to form the carton, of means for applying adhesive to portions of the blank, means for tucking inwardly said portions of the blank to form a leg, and means for feeding the blank from the last mentioned means to said carton forming means.

18. In a machine for making a carton having depending legs from a blank, the combination with means for folding the blank to form the carton, of means for applying adhesive to portions of the blank, means for tucking inwardly said portions of the blank to form a leg, means for feeding the blank from the last mentioned means to said carton forming means, and means for applying adhesive to other portions of the

blank while the latter is being transferred by said feeding means.

19. A machine for making a carton having depending legs from a blank, comprising a plate over which the blank may lie with an edge portion extending beyond an edge of the plate, a finger positioned above the blank outside said edge of the plate and inwardly from the outwardly extending edge of the blank, and means for causing relative movement between the plate and finger to fold portions of the blank downwardly and inwardly over the edge of the plate to form a tuck in the body of the blank, said finger lying in the fold of the tuck when the latter is being formed.

20. A machine for making a carton having depending legs from a blank, comprising a plate over which the blank may lie with an edge portion extending beyond an edge of the plate, a finger positioned above the blank outside said edge of the plate and inwardly from the outwardly extending edge of the blank, means for holding said outwardly extending edge of the blank, and means for causing relative movement between the plate and finger to fold portions of the blank downwardly and inwardly over the edge of the plate to form a tuck in the body of the blank, said finger lying in the fold of the tuck when the latter is being formed.

CLAUDE M. STITT. 30
